Issued Oct 11, 1872.

UNITED STATES PATENT OFFICE.

WALTER M. CONGER, OF NEWARK, NEW JERSEY.

DESIGN FOR STOVE PLATFORM OR SUPPORT.

Specification forming part of Design No. 6,202, dated October 15, 1872.

To all whom it may concern:

Be it known that I, WALTER M. CONGER, of Newark, Essex county, New Jersey, have invented a Design for Stove-Support, of which the following is a specification:

The stove-support is intended to be struck up from sheet-zinc or other thin metal, and japanned or otherwise decorated.

The design is produced by embossing the surfaces by means of dies. The nature of the design is represented in the accompanying illustration, to which reference is made, and which forms a part of this specification.

The center is raised, as indicated by A. A considerable surface toward each corner, which receives the legs of a four-legged stove, is made plain, as indicated by B. A portion of the surface along the middle of each side, which is liable to receive one of the legs of a three-legged stove, is made plain, as indicated

by C. The bead D completes the design. This bead leads outward and inward, as shown, between the spaces B and C.

The entire surface, or any portion of it, may be decorated with any tasty figures or ornamentation which will not interfere with my design, the distinctive character of which is found in the central raised portion A, plain surfaces B and C, and bead D.

What I claim as my invention is—

The design for stove-support, substantially as herein represented and described.

In testimony whereof I have hereunto set my hand this 24th day of September, 1872, in the presence of two subscribing witnesses.

WALTER M. CONGER.
